US00D992305S

(12) United States Design Patent (10) Patent No.: US D992,305 S
He (45) Date of Patent: * Jul. 18, 2023

(54) TOOL COLLECTION SHELF

(71) Applicant: Ming He, Chengdu (CN)

(72) Inventor: Ming He, Chengdu (CN)

() Term: 15 Years

(21) Appl. No.: 29/791,342

(22) Filed: Jan. 8, 2022

(51) LOC (14) Cl. 08-08

(52) U.S. Cl.

USPC D6/572

(58) Field of Classification Search
